INCINERATOR

Joseph Sharp, Chicago, Ill.

Application September 9, 1940, Serial No. 355,894

4 Claims. (Cl. 110—18)

The present invention relates to incinerators and has for its main object the provision of a device for burning waste material.

A still further object of the present invention is the provision of the device broadly consisting of a grate support upon which a suitable receptacle may be positioned and in a hinged relation therewith within which refuse and other waste material may be placed for the purpose of burning and which receptacle may be in a hinged relation with the grate for the purpose of tilting the same angularly with respect to the grate for the purpose of removing from the grate the unconsumed waste material.

A still further object of the present invention is the provision of an incinerator of the type indicated, and which may be hingedly affixed to a suitable anchor embedded in the ground, and in which the grate and the receptacle positioned thereover within which the refuse and waste material may be consumed, may be angularly shifted upon said anchor so as to remove ashes and other unconsumed particles of waste material from the ground which may fall thereon through said grate and from said receptacle.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views;

Fig. 1 is a side elevational view of the device with all component parts thereof in an operative position;

Fig. 2 is a fragmentary side elevational view of the device with the grate and the receptacle in an elevated, angularly swung inoperative position;

Fig. 3 is a top plan elevational view of the device; and

Fig. 4 is an end elevational view of the device.

Referring in detail to the present drawing, there is shown an anchor which includes a pair of upright spaced bars 10 with a transverse brace 11 connecting the latter adjacent their lower ends. Said anchor is adapted to be embedded in a cement block 12, or driven into the ground.

The device further includes grate 13 supported upon legs 14, one extending from each corner of the grate. Integrally formed with, and later-

ally projecting from one side of grate 13 is a pair of arms 15. Said arms 15 are apertured at their free ends and are so spaced as to contact by their outer faces with the inner faces of bars 10, as is clearly seen in Fig. 3. The upper ends of said bars 10 are likewise apertured so that through all of the apertures shaft 16 may be extended, by means of which arrangement grate 13 may be pivoted to said anchor for angular swinging movement.

The device further includes a cylindrical receptacle 17 open at both of its ends, adapted for positioning by its lower end upon said grate 13 and arms 15, and wherein refuse and waste material may be thrown through the upper end to grate 13 upon which the same may be consumed. Affixed to the outer periphery of said cylindrical receptacle 17 and adjacent its lower end, by means of rivets 18 or other suitable means, is a pair of hinges 19. Each of said hinges constitutes an upright portion, and a laterally extending, horizontal leg portion, which terminates in loop 20 through which said shaft 16 is adapted to extend. It is noted that loops 20 of both of said hinges 19 are positioned upon said shaft 16 and within the space thereof defined by arms 15.

From the hereinabove description it will be apparent that receptacle 17 is adapted for angular swinging motions upon said shaft 16 to assume an outwardly swung, inoperative position illustrated in Fig. 2, and without in any wise affecting the operative position of grate 13. Also grate 13 is adapted to angularly swing upon said shaft 16, either with or without receptacle 17 to assume a range of inoperative positions indicated in Fig. 2. It will therefore be seen that when receptacle 17 is angularly shifted into an inoperative position, access will be had to grate 13 and to the unconsumed refuse and waste material that may remain upon said grate 13. In order to sweep the ashes as well as other products of combustion or unconsumed particles of waste, from the ground or from block 12 immediately below said grate 13, the latter may be angularly shifted into its inoperative position indicated in Fig. 2.

From the hereinabove description it will be seen that the incinerator forming a subject matter of the present application is extremely practicable in that it comprises only a few parts, so connected that one may not be displaced from the others, and maintained in the place where the burning of the refuse is to be intended by means of either permanently or temporarily driven anchor into the ground or a cement block.

A further advantage of the present device consists in the receptacle and the grate being angularly shiftable so as to permit access to ashes and unconsumed portions of waste for the purpose of removing the same from the place of incineration.

While there is described herein a preferred embodiment of the present invention, it is nevertheless to be understood that minor changes may be made therein without departing from the spirit and scope of the invention as claimed.

What I claim as new is:

1. An incinerator comprising an anchor, a grate, and a receptacle adapted to be positioned upon said grate, said grate and said receptacle being pivoted upon said anchor for selective angular shifting movement with respect thereto.

2. An incinerator comprising an anchor, a grate, and a receptacle adapted for positioning upon said grate, said receptacle being open at both of its ends, whereby by one end it may be positioned upon said grate and through the other may receive the refuse to be consumed upon said grate, said grate and said receptacle

being in pivotal relation with said anchor whereby the same may successively be angularly shifted with respect to said anchor.

3. An incinerator comprising an anchor adapted to be driven into the ground for the purpose of assuming a rigid and substantially upright position, a grate, and a receptacle normally positioned upon said grate, said grate and said receptacle being in a pivotal relation with said anchor for selective angular shifting movement with respect thereto.

4. An incinerator comprising a pair of upright bars adapted for anchoring in the ground, a grate, a pair of arms extending from said grate, a receptacle adapted for positioning upon said grate, and a shaft interengaging said bars and said arms for pivotally connecting said grate to said bars, and a hinge connection between said receptacle and said shaft, said receptacle and said grate being selectively adapted for angular swinging movement with respect to said bars and upon said shaft.

JOSEPH SHARP.
